UNITED STATES PATENT OFFICE.

PATRICK F. DUNDON, OF SAN FRANCISCO, CALIFORNIA.

INCINERATING-FURNACE.

1,095,493.

Specification of Letters Patent.

Patented May 5, 1914.

Application filed July 3, 1911. Serial No. 636,675.

To all whom it may concern:

Be it known that I, PATRICK F. DUNDON, a citizen of the United States, residing at San Francisco, in county of San Francisco and State of California, have invented certain new and useful Improvements in Incinerating-Furnaces, of which the following is a specification.

My invention relates to an improvement in incinerating furnaces, and the object is to provide a simple, effective arrangement of elements to take care of waste and refuse, and it consists in certain novel features of construction and combinations of parts 15 which will be hereinafter described and pointed out in the claims.

In the accompanying drawings:

Figure 1 is a front elevation of the incinerating furnace, Fig. 2 is a longitudinal vertical section on line 2—2 of Fig. 3, Fig. 3 is a top plan view of the feeding floor partly in section showing one of the units in section, taken on line 3—3 of Fig. 2, Fig. 4 is a transverse vertical section taken on line 4—4 of Fig. 3, Fig. 5 is a view showing a modified form of the air intake for force draft, and Fig. 6 is a detail view of the expansion springs and buck-stays.

The furnace in its preferred form—I have illustrated it in Fig. 3—comprises two main units, and each unit comprises four cells 1, 1, one combustion chamber 2, one supplementary chamber 3, one boiler-cell 4, and a water tube boiler 5 therein, one air heater cell 6 with tubular air heaters 8; 8, therein, and a water heater cell 7, having tubular water heater 9, located therein.

Beneath the cells and combustion chamber are the usual grates 10, 10, and above is the arch 11, and above the arch 11 and between it and the feeding floor 12 is a hot air chamber 13, which is fed by an air intake pipe 14 which extends up to a point somewhere near the ceiling of the building in which the furnace is placed, its object being to withdraw the foul odors therefrom which are heated in the heating chamber 13, and afterward conducted to a point beneath the grates, and through the combustion chamber 50 as will now be explained.

An air pipe 15 leads from the air space or chamber 13 at a point preferably just above the supplementary chamber 3 over the boiler cell, it being approximately the 55 width of the unit at the point where it leaves the air space or chamber 13, as clearly

shown in the lower unit of Fig. 3, thence tapering to approximately the horizontal area of the air heater 8, as also shown in the lower unit of Fig. 3, so that the air is further heated as it passes through the tubes of the air heater, as will be more fully explained hereinafter. From this point, the air is drawn out through a suction pipe 16 by the circulating fan 17, and thence returned by the hot air pipe 18 to the hot air flue 19, whence it discharges laterally through openings beneath the grates, as shown in Fig. 2, which openings are controlled by doors 20, 20 operated by any practical 65 method for opening and closing the same. In this way, the air is thoroughly heated before it passes up through the grates, and also a perfect ventilation is provided, and the noxious odors of the building are completely 70 removed.

It is evident that the air from the building might be taken in through an air intake stack directly to the air heater, if desired, as shown in Fig. 5, instead of passing 75 through the air space or chamber 13. Notwithstanding this, however, it is my preference to take it through the entire length of the air space or chamber 13, for obvious reasons. First, it gets the benefit of the heat 80 radiating from the arches of the furnace; and second, it has the secondary and very important function of keeping the feeding floor 12 above, cool, or sufficiently cool so that it is possible to walk or drive over it 85 with comfort.

Charging hoppers 21, 21, are provided over each cell 1, 1, and these are provided with covers which may be supported and carried on an overhead track, or in any other 90 approved manner. Beneath these charging hoppers is the drying hearth 22, as shown clearly in Fig. 4, this drying hearth being directly over the air flue 19, so that the hot air circulated and retained by the flues is 95 further utilized to dry the material to be incinerated before it is raked over on the grates, access to which may be gained through the usual doors 23, 23, just over the grates.

A by-pass 24 extends around the boiler cell, as shown clearly in Fig. 3, and damper 25 shuts off communication from the boiler cell thereinto, and damper 28 in the supplementary chamber is opened to cause the 100 products of combustion from the cells 1, 1, and the combustion chamber 2 to pass

through the supplementary chamber and boiler cell, and thence around the tubes of the tubular air and water heaters 8 and 9, and thence to the stack 27. Should occasion therefore require cutting out the boiler cell in the event of repairs to the water tube boiler, the dampers 25 and 28 representing the outlet and inlet of the boiler cell are closed, and the damper 26 in the supplementary chamber is opened into the by-pass 24. In other words, under ordinary conditions, all products of combustion flow from the cells 1, 1, and combustion chamber 2 into the supplementary chamber 3, and thence into the boiler cell 4, and then into the by-pass 24, and thence through the tubular air and water heaters 8 and 9, and out to the stack; but when the water tube boiler is out of commission, or it is desirable to cut the boiler cell out, this may be done without interfering with the general use of the furnace by simply opening the damper 26 and closing the dampers 25 and 28.

From the ash-pits 29 beneath the grates, the ashes are removed in any approved manner.

The buck-stays 30, 30, are held by the usual tie-bolts 31, 31; to accommodate the expansion of these tie-bolts 31, 31, I have provided double-truss springs 32, 32, shown enlarged in Fig. 6, and the nuts 33, 33, at each end of the bolts; and wherever required the end and back walls will be completely bound with steel plates as well as horizontal beams between the buck-stays.

Whenever deemed necessary, there will be placed vent valves 34, 34, which operate automatically with the slightest excess of pressure to allow the escape of gases due to excessive pressure or gas expansion within the furnace.

An excessive degree of heat is obtained in the combustion chamber 2 by concentration therein and accumulation of the products of combustion, and consequently it is employed for the disposal of dead animals, and it might also be utilized for other purposes.

Having fully described my invention, what I claim as new and desire to secure by Letters Patent, is:—

1. An incinerating furnace comprising a combustion chamber, a grate in the bottom of the latter, an air heater, an air pipe leading into the latter for taking air and removing noxious odors from the building in which the furnace is placed, a suction pipe leading from the air heater, a fan located therein, an air flue leading from the fan approximately throughout the length of the furnace at one side of the grate, and having a lateral opening beneath the grate, and a drying hearth located above the air flue at one side of the grate.

2. A furnace comprising a plurality of cells having the usual grates and doors above and below the grates, a drying hearth at one side of the grates, feeding hoppers above the drying hearth, and an air flue extending continuously beneath the drying hearth, an air heater, an air pipe through which air is drawn to the heater, an air circulating mechanism for creating a circulation of air through the air pipe and air heater, and feeding it to the air flue, and outlets from the air flue beneath the grates.

In testimony whereof I affix my signature, in the presence of two witnesses.

PATRICK F. DUNDON.
